(57) CLAIM

The ornamental design for a ground coffee dispenser, as shown and described.

DESCRIPTION

A portion of the disclosure of this design patent document contains material which is subject to copyright protection. The copyright owner has no objection to the facsimile reproduction by anyone of the patent document or the patent disclosure, as it appears in the U.S. Patent and Trademark Office patent files or records, but otherwise reserves all rights under the copyright laws of the United States (17 U.S.C. § 106).

FIG. 1 is a perspective view of a ground coffee dispenser, in accordance with the present invention.

FIG. 2 is a top view of a ground coffee dispenser, in accordance with the present invention.

FIG. 3 is a front view of a ground coffee dispenser, in accordance with the present invention.

FIG. 4 is a right lateral view of a ground coffee dispenser, in accordance with the present invention, the left lateral view being a mirror image thereof.

FIG. 5 is a back view of a ground coffee dispenser, in accordance with the present invention; and,

FIG. 6 is a bottom view of a ground coffee dispenser, in accordance with the present invention.
